UNITED STATES PATENT OFFICE.

GEORGE THOMAS MARTIN, OF SMITH'S FALLS, CANADA.

VARIABLE-SPEED GEARING FOR BICYCLES.

SPECIFICATION forming part of Letters Patent No. 681,718, dated September 3, 1901.

Application filed May 31, 1901. Serial No. 62,515. (No model.)

To all whom it may concern:

Be it known that I, GEORGE THOMAS MARTIN, a subject of the King of Great Britain, residing at Smith's Falls, county of Lanark, Province of Ontario, Canada, have invented 5 certain new and useful Improvements in Variable-Speed Gearing for Bicycles; and I do hereby declare that the following is a full, clear, and exact description of the invention, such as will enable others skilled in the art 10 to which it appertains to make and use the same.

My invention relates to improvements in variable-speed gearing for bicycles and other 15 machinery; and the primary object of the invention is the production of a compact, simple, strong, and efficient mechanism capable of easy operation when it is desired by the rider to change from a high speed to a low 20 speed, as when the road changes from a level to an upgrade or hill, while at other times the speed of the gearing can in like manner be changed from a low speed to a high speed in the event of the rider desiring to spurt or 25 travel rapidly over a level stretch of a road.

Further objects and advantages of the invention will appear in the course of the subjoined description, and the novelty in the combination, construction, and arrangement 30 of parts will be defined by the claims.

In the drawings hereto annexed, forming a part of this specification, Figure 1 is an end elevation with a part of the crank-hanger and the casing broken away and showing portions 35 of a changeable-speed gearing embodying my improvements. Fig. 2 is a vertical transverse sectional elevation taken in the plane of the dotted line 2 2 on Fig. 3. Fig. 3 is a sectional elevation with a part of the casing 40 broken away and looking in a direction at right angles to Fig. 2, the plane of said section being indicated by the dotted line 3 3 on Fig. 1. Fig. 4 is a sectional plan view taken in the horizontal plane of the pedal-shaft and 45 representing another embodiment of my changeable-speed gearing, which is especially adapted to the bevel-gearing commonly employed in chainless bicycles.

The same numerals of reference denote corresponding parts in the several figures of the drawings.

5 designates the crank-hanger, which is

joined or connected in any of the approved ways with the seat-post tube 5^a and the inclined front reach 7^b of the ordinary bicycle-frame. The end portions of this crank-hanger are widened or expanded, as indicated at 6 6^a, and these expanded portions are formed with the integral plates 7 7^a, and, furthermore, these plates terminate in the annular rims 8 8^a, all as more clearly shown by Figs. 2 and 4. The expanded or widened ends 6 6^a and the rims 8 8^a of the crank-hanger are interiorly screw-threaded, as indicated at 9 10, respectively. 65

11 12 designate the removable face-plates, each of which is provided with an inwardly-extending flange 13, which is formed with an external or male screw-thread, and these face-plates 11 12 have the threaded flanges 13 thereof screwed into the female threaded portions 10 of the rims 8 on the crank-hanger, whereby the face-plates are removably and fixedly attached to the crank-hanger, and they serve to close the expanded end portions 75 of said hanger in such a way that provision is made for the accommodation of the driving element and the primary gear member of a train of multiplying-gearing, all as will hereinafter more fully appear. 80

14 designates the pedal-shaft, which is supported by ball-bearings in the opposite face-plates 11 12. As is usual in the art, the pedal-shaft is externally threaded, as at 14^a, in order to receive the bearing-cones 15, which 85 are held against turning by the check-nuts 16, said cones having operative relation to the series of bearing-balls 17, which are confined in the cups 18, the latter being screwed into the central portions of said face-plates 90 11 12. The described construction is the preferred embodiment of the ball-bearings for the pedal-shaft, but of course any equivalent bearing may be adopted.

20 designates a hollow or tubular mandrel, 95 the same loosely surrounding the pedal-shaft and supported within the crank-hanger by ball-bearings, so that said hollow mandrel is entirely independent of the pedal-shaft and its supporting devices. This hollow mandrel 100 20 is somewhat shorter than the pedal-shaft, so that the mandrel will be housed or contained entirely within the chamber formed by the crank-hanger and the face-plate there-

of, and with this hollow mandrel is associated the driving element for the bicycle propulsion, the same being represented by Fig. 2 in the form of a sprocket-wheel 21 when the improved variable-speed gear is used on bicycles having sprocket-chain-and-wheel gearing as the propulsion devices. As will be evident by an inspection of Fig. 4, however, this driving element 21 is in the form of a bevel-gear 22 when the improved variable-speed gearing is used as a means for driving chainless bicycles and kindred machinery. The sprocket-wheel 21, forming the driving element for the chain of the propulsion mechanism, has its toothed rim disposed in the space inclosed by the integral plate 7^a and the face-plate 12 at the right-hand portion of the crank-hanger, and this toothed rim is secured by bolts 21^a to the inner wheel-section 21^b, the latter being made fast with the hollow mandrel 20 at the right-hand end thereof.

To the end portions of the hollow mandrel 20 are secured the bearing-cones 23, disposed in operative relation to the series of bearing-balls 24, that are confined in the cups 25, the latter being screwed into the threaded portions 9 of the widened or expanded ends 6 6^a of the crank-hanger. (See Fig. 2.) It is evident that the hollow mandrel is thus mounted in the crank-hanger so as to turn freely therein, and that it is independent of the pedal-shaft, which it serves to partly inclose or house. This hollow mandrel greatly exceeds the diameter of the pedal-shaft in order that the two clutch-sections, to be hereinafter described, may be properly fitted within the hollow mandrel and around the pedal-shaft.

I will now proceed to describe the train of multiplying-gearing and the means for supporting the same. The primary member 26 of this train of gears is housed or contained in the space formed by the integral plate 7^a and the face-plate 11 at the left-hand end of the crank-hanger, and this primary member is in the form of a dished bevel-gear having oblique gear-teeth 26^a and an integral hub 27, the latter being secured firmly to the pedal-shaft 14 and extending into the left-hand end 50 of the hollow mandrel 20, whereby said primary gear member is made fast with the pedal-shaft, so as to rotate therewith at all times. The crank-hanger is provided at its top portion with an integral enlargement 55 forming a bearing-lug 28 for the right-hand portion of an inclined arbor or spindle 30, the left-hand portion of which arbor is supported in a bearing-lug 29, secured to the corresponding portion of the crank-hanger and in a 60 plane above the lug 28, whereby provision is made on the crank-hanger for supporting the arbor or spindle at an angle to the axis of the pedal-shaft 14. Loosely fitted on the arbor or spindle, so as to partake of the inclination 65 thereof, is a sleeve or bushing 31, the length of which is equal to the space between the lugs

28 29, whereby the sleeve is loosely mounted on the arbor, and it is held against endwise displacement by the lugs. The ends of said sleeve are exteriorly screw-threaded for the 70 reception of the bearing-cones 32 and their check-nuts 33, and these cones are in co-operative relation to the bearings-balls 34, the latter being confined in the cups 35. A hollow shaft 36 is provided with expanded ends 75 37, the same being interiorly and externally screw-threaded. The cups 35 are threaded into the female threaded portions of the expanded ends, as shown by Fig. 2, so as to support the end portions of the hollow shaft 80 36 loosely upon the bushing or sleeve, that in turn is held in place by the arbor or spindle 30. It will be noted that the hollow shaft 36 surrounds and is concentric with the sleeve and the spindle, and, furthermore, that the 85 hollow shaft partakes of the inclination of said sleeve and the spindle, thus making provision for accommodation of the gear-pinions 38 39, which are of different sizes. The gear-pinion 38 is screwed to the male thread left-hand end 37 of the hollow shaft, and said gear-pinion is arranged to have intermeshing engagement with the primary gear member 26 of the train of gears. The other gear 39 is screwed to the male threaded right-hand 90 end 37 of the hollow shaft, so that it will rotate with the shaft when the latter is driven from the pedal-shaft 14 by the agency of the primary gear member 26 and the intermediate gear 38 of the train of gears. The gear 38 and a part of its bearing is arranged to project through a slot or opening 40, which is provided in the left-hand integral plate 7 of the crank-hanger, and another slot or opening 41 is provided in the crank-hanger proper 100 at a point which permits the right-hand gear-pinion 39 to project through the crank-hanger in order that said gear 39 may have intermeshing engagement with a shiftable gear 42, the latter constituting the final member of the 105 train of multiplying-gears. The hollow shaft 36 and the gears 38 39 thereon are protected from dust and dirt by an inclosing casing 43, which is secured to the upper portion of the expanded ends of the crank-hanger. 110

The hollow mandrel 20 is provided with a series of longitudinal slots 44, preferably three in number, and said mandrel is furthermore provided with a like series of keys 45, the same extending longitudinally of the mandrel in parallel relation to the slots and alternating with said slots, as will be seen by reference to Fig. 3.

The hub 46 of the shiftable gear 42, which forms the final member of the train of reducing-gearing, is snugly fitted upon the hollow mandrel, so that it is capable of a slideable movement thereon, and the inner face of this gear-hub 46 is provided with the grooves in which are seated the series of longitudinal keys 45, whereby the shiftable gear 42 is made fast with the hollow mandrel, so

that it will turn at all times therewith and yet is capable of the slidable adjustment on said mandrel. The rigid slidable connection between the shiftable gear 42 and the hollow mandrel is supplemented by the employment of the series of bolts 47, the same having their heads seated flush with the gear-hub and passing through the slots 44 of the hollow mandrel, as shown by Figs. 2 and 3, thus making provision for the bolts sliding in the slots when the shiftable gear is adjusted on the hollow mandrel. These bolts serve, furthermore, as the means for operatively connecting the shiftable clutch member 48 to the shiftable gear 42, said clutch member being arranged within the crank-hanger so as to loosely surround the pedal-shaft 14.

It is to be observed that the gear 42 and the clutch member 48 are disposed outside of 20 and within the hollow mandrel, respectively; but the bolts 47 serve to unite the clutch member and the gear together in a manner to insure simultaneous movement of the parts. This clutch member 48 has its working face 25 49 disposed in opposing relation to a similar working face 51 on the fast clutch member 50, the latter being made fast with the pedal-shaft, near the left-hand end thereof, and adapted to turn with said pedal-shaft at all 30 times. Furthermore, the fast clutch member 50 lies within the hollow mandrel 20 in the path of the working face on the slidable clutch member, and, if desired, this fast clutch member 50 may be formed on the hub 35 27 of the primary member 26 of the multiplying-gear.

Any suitable means may be provided for giving the slidable adjustment to the gear 42 and the clutch member 48, associated therewith, and as one means for giving the described adjustment to these parts I have shown the mechanism as equipped with a rocking fork or yoke 52, the latter being movable with a rock-shaft 53, journaled in appropriate bearings 54 at the lower portion of the crank-hanger, as shown more particularly by Fig. 3. This fork or yoke is arranged to straddle or loosely embrace the under side of the hub 46, forming a part of the shiftable gear 42, and the end portions of this yoke or fork have the pins 55, on which are loosely supported the friction-rolls 56, that are fitted loosely in an annular groove 57, which is provided in the hub 46 of the shiftable gear, thus 45 making provision for the operative connection of the fork or yoke with the gear at all times. The rock-shaft 53 is provided at one end with a crank-arm 58, to which is connected a shipping-rod 59, the latter adapted to be operated by any suitable appliance on the bicycle and located within convenient reach of the rider. Under ordinary conditions of service the gear 42 (to the hub of which is fixed the clutch member 48 by the stub-screws 47) is in 55 mesh with one of the intermediate members 39, which form a complete train of gearing. Under these conditions of adjustment the mo-

tion of the pedal-shaft is transmitted through the gear-train 26 38 39, which causes the sprocket-wheel 21 21^a to revolve with a greater 70 speed than the pedal-shaft 14. The high-speed elements of the bicycle are thus adapted for service in order to propel the machine under the highest speed attainable by the use of the invention on level or other favorable 75 surfaces. When the rider desires to ascend a hill and bring into service the lower speed, it is only necessary to manipulate the said device, which moves the rod 59 and the rock-shaft 53, so as to change the position of the 80 yoke or fork 52. This change in position of the fork moves the gear 42 from intermesh with the gear 39 and by continuing the same movement of the rod 59 carries the clutch member 48 into mesh with the clutch member 85 50, which clutches are securely locked together by the toothed portions 51 and 49, and thereby the pedal-shaft 14 and the hollow mandrel 20 revolve as one, and consequently at a reduced speed. The train of gears 26 38 90 39 42, though still revolving, are disconnected at 39 and 42, and therefore are not doing any work as a propelling medium. By my invention it is possible to obtain a high or low speed, as required, and the said speed can be 95 varied by the relative sizes of the sprocket-wheels or gear-wheels.

The embodiment of the invention represented by Fig. 4 contemplates the same elements as hereinbefore shown and described, 100 except that for the sprocket-wheel 21 I employ the bevel-gear 22 as the driving element, said bevel-gear being made fast with the right-hand end of the hollow mandrel 20. The driving element 22 has intermeshing engagement with a bevel gear-wheel 60, which is secured to the forward end of a counter-shaft 61, the latter extending loosely through one of the horizontal rear forks 62 of the machine-frame in a manner familiar to those skilled 110 in the art.

Changes within the scope of the appended claims may be made in the form and proportion of some of the parts, while their essential features are retained and the spirit of the invention is embodied. Hence I do not desire to be limited to the precise form of all the parts as shown, reserving the right to vary 115 therefrom.

Having thus described my invention, what 120 I claim as new is—

1. In a variable-speed gear of the class described, the combination with a pedal-shaft, of a single continuous hollow mandrel supported independently of the pedal-shaft and 125 provided with a driving element, a two-part clutch having one member made fast with the pedal-shaft and its other member connected to the hollow mandrel to slide thereon and to turn therewith, a train of multiplying-gearing driven by the pedal-shaft and having its final member made fast with the shiftable clutch member, and adapted, under certain conditions, to propel the hollow mandrel, 130

and means for shifting the slidable clutch member and the final member of the gear-train, substantially as described.

2. In a variable-speed gear of the class described, the combination with a pedal-shaft, of a single continuous hollow mandrel provided with a driving element, means for independently supporting the hollow mandrel and the pedal-shaft in concentric relation, a train of multiplying-gearing having the driving member thereof propelled by the pedal-shaft and with the final member of said gear-train fitted on the hollow mandrel, a two-part clutch having one member thereof secured fast to the pedal-shaft, and means connecting the final member of the gear-train and the shiftable clutch member fast with one another and also connecting the same slidably with the hollow mandrel, substantially as described.
3. In a variable-speed gear of the class described, the combination with a pedal-shaft, of a hollow mandrel provided with a driving element, a train of multiplying-gearing having the primary member made fast with the pedal-shaft and its final member shiftably connected in fast relation with the hollow mandrel, and a two-part clutch having one member fast with the pedal-shaft and a shiftable member connected with the hollow mandrel and the final member of the train, said shiftable clutch member and the final member of the gear-train being fast one with the other and both having shiftable relation to the hollow mandrel and adapted to turn at all times therewith, and means for adjusting the shiftable clutch member and the shiftable gear, substantially as described.

4. In a variable-speed gear of the class described, the combination of a crank-hanger having two independent sets of ball-bearings disposed in different planes, a pedal-shaft mounted in one set of ball-bearings, a hollow mandrel mounted in the other set of ball-bearings independently of the pedal-shaft and provided with a driving element, a two-part clutch having one member fast with the pedal-shaft and the other member connected fast with the hollow mandrel so as to be shiftable thereon, a train of multiplying-gearing arranged for its primary member to be fast with the pedal-shaft and for its final member to be connected shiftably to the hollow mandrel, and means for adjusting the shiftable clutch member and the final member of the train of gearing, substantially as described.

5. In a variable-speed gear of the class described, the combination of a crank-hanger having the expanded end portions and the removable face-plates, a set of ball-bearings supported in the expanded end portions of the crank-hanger, another set of ball-bearings supported in said face-plates, a pedal-shaft mounted in the bearings of the face-plates, a hollow mandrel supported by the bearings of the crank-hanger, a two-part clutch having its members fast with the pedal-shaft and the mandrel respectively, means for shifting

one of the clutch members, and a train of multiplying-gearing having the primary member fast with the pedal-shaft and its final member fast with the hollow mandrel, substantially as described.

6. In a variable-speed gear of the class described, the combination with a pedal-shaft, of a hollow mandrel provided with a driving element, a primary gear member fast with the pedal-shaft, an independently-supported shaft having two gears one of which meshes with the primary gear member, a shiftable gear fast with the hollow mandrel and arranged to mesh with the other gear of the independently-supported shaft, and a two-part clutch having one member fast with the pedal-shaft and its other member connected with the hollow mandrel and with the shiftable gear, said shiftable clutch member and the shiftable gear being made fast one with the other and both having shiftable relation to the hollow mandrel and adapted to turn at all times therewith, substantially as described.

7. In a variable-speed gear of the class described, the combination with a pedal-shaft, of a hollow mandrel provided with a driving element, a primary gear member fast with the pedal-shaft, a stationary spindle or arbor in inclined relation to the pedal-shaft, a bushing on said arbor, a hollow pedal-shaft supported by ball-bearings on the bushing and provided with gears one of which meshes with the primary gear member, a shiftable gear made fast with the hollow mandrel and having intermeshing engagement with the other gear of the hollow shaft, and a two-part clutch one member of which is connected with the hollow mandrel and with the shiftable gear, substantially as described.

8. In a variable-speed gear of the class described, the combination with a pedal-shaft, of a hollow mandrel provided with the slots, a shiftable gear keyed to the hollow mandrel and having a grooved hub, a shiftable clutch member within the hollow mandrel, bolts attached to the shiftable gear, and said clutch member arranged to travel in the slots of the hollow mandrel, a rocking yoke engaging with the hub of said shiftable gear, a fast clutch member on the pedal-shaft, a primary gear member fast with the pedal-shaft, and an independently-supported shaft having gears arranged to mesh with the primary gear member and with the shiftable gear, substantially as described.

9. A variable-speed gear of the class described comprising a crank-hanger provided with face-plates and with independent sets of ball-bearings and with an upper casing, a pedal-shaft journaled in one set of ball-bearings, a hollow mandrel journaled in the other set of ball-bearings and provided with a driving element, the fast and shiftable clutch members secured to the pedal-shaft and having slidable connection with the hollow mandrel respectively, a primary gear member on the pedal-shaft, a shiftable gear member hav-

ing operative connection with the hollow mandrel and with the shiftable clutch member, and an independently-supported shaft arranged within the casing and having gears disposed to mesh with the primary gear member and with the shiftable gear respectively, substantially as described.

In witness whereof I have hereunto set my hand in the presence of two witnesses.

GEORGE THOMAS MARTIN.
